UNITED STATES PATENT OFFICE.

GEORGE C. HOHEIN, OF STAUNTON, VIRGINIA.

SYRINGE.

1,242,806.

Specification of Letters Patent.

Patented Oct. 9, 1917.

Application filed March 10, 1916. Serial No. 83,408.

To all whom it may concern:

Be it known that I, GEORGE C. HOHEIN, a citizen of the United States, residing at Staunton, in the county of Augusta and 5 State of Virginia, have invented new and useful improvements in Syringes, of which the following is a specification.

The invention relates to syringes, and more particularly to the class of sanitary 10 hot water and air drying syringes.

The primary object of the invention is the provision of a syringe of this character, wherein the construction thereof is novel in 15 form to develop a thoroughly sanitary condition and healthful state of the membrane in the female organ.

Another object of the invention is the provision of a syringe of this character, wherein the parts thereof are readily and easily separated, so as to permit the easy cleaning 20 thereof, or the sterilizing of the same.

A further object of the invention is the provision of a syringe of this character, wherein any pus or matter can be readily 25 drawn from the membrane of the female organ, and thereafter the said membrane thoroughly dried, thereby leaving the same and the pores in a sanitary, firm and healthy condition.

30 A still further object of the invention is the provision of a syringe of this character, which is simple in construction, thoroughly reliable and efficient in operation, strong, durable and inexpensive in manufacture.

35 With these and other objects in view, the invention consists in the features of construction, combination and arrangement of parts as will be hereinafter fully described, illustrated in the accompanying drawing, 40 and pointed out in the claims hereunto appended.

In the accompanying drawing:

Figure 1, is a side elevation of a syringe constructed in accordance with the invention.

45 Fig. 2, is a vertical longitudinal sectional view thereof.

Fig. 3, is a perspective view of the suction nozzle detached.

50 Fig. 4, is a perspective view of the inner perforated nozzle.

Fig. 5, is a sectional view on the line 5—5 of Fig. 1.

55 Similar reference characters indicate corresponding parts throughout the several views in the drawing.

Referring to the drawing in detail, the syringe comprises a handle member 10, preferably tapered from one end to the other, and is formed with a central longitudinal bore 11, which communicates with a socket 12, in the small end of the member, while in this bore 11, is a tube 13, formed at one end with a perforated spray head 14, adapted to fit within the socket 12, in the smaller end of the handle, the opposite end of the tube 13, being screw threaded at 15, for the detachable engagement of the same in a nipple 16, of a compressible bulb 17, having a removable cap or plug 18, normally closing a filling opening therein, so that the bulb can be filled with liquid.

The smaller end of the handle member 10, is formed with inner and outer screw threads 19 and 20, respectively, externally thereof, and detachably engaged with these outer threads is an inner nozzle 21, while detachably engaged with the inner threads is an outer nozzle 22, the latter being formed with a plurality of internal teats 23, providing cells or pockets 24, opening through the outer surface of the said nozzle to serve as vacuum cups therein.

The inner nozzle 21, is formed with a plurality of perforations 25, for the circulation of water within the outer nozzle 22, for the expanding and contracting thereof so that corresponding action will be imparted to the cells or pockets 24, for creating a suction upon the membrane of a female organ, to extract pus and matter therefrom, when the instrument is in use. These cells or pockets 24 extend only through the outer face of the nozzle 22 and the inner ends are closed so as not to communicate with the space formed between the inner and outer nozzles. When water is forced into the space between the inner and outer nozzles 21 and 22 the latter nozzle bulges, thereby flattening the cells or pockets 24' therein, and on the water being drawn out of said space the said cells or pockets contract or relax which will exert an alternate pressure and grip on the skin of the wall of the cavity in which the device is inserted and thus draw out pus or other foreign matter from the pores therein, as will be clearly evident. When the nozzle 22 is expanded by the internal pressure and the cells or pockets 24' flattened as stated, air will be forced from the latter so that on subsequent relaxation of the pocket they will set up a suction on

the membrane of the cavity with which they are in contact.

The nipple 16, is provided with a hand operated cut off valve 26, which controls the flow of liquid from the bulb to the nozzle or tube 13, within the handle. Of course it will be apparent that the outer nozzle 22, can be taken off and the inner nozzle 21, will permit the use of the instrument as a douche, that is to say either as a liquid sprayer or an air atomizer for the drying of the membrane or pores of the skin, in the use of the syringe.

From the foregoing it is thought that the construction and manner of use of the syringe will be clearly understood and therefore a more extended explanation has been omitted.

Having thus described my invention, I claim:

1. A syringe comprising a handle having a central longitudinal bore therein, a tubular stem within the bore in the handle, a compressible bulb detachably connected with one end of the stem, a hand-operated valve controlling communication between the bulb and the stem, a perforated nozzle on the stem and seated within the handle, an inner nozzle detachably connected with the handle and having perforations, an outer nozzle detachably connected with the handle and having a plurality of teats struck inwardly to form suction pockets opening through the outer surface thereof.

2. A syringe of the class described com-

prising a handle tapered from one end to the other thereof and having a central bore, a tubular stem fitted within the bore, a flared perforated nozzle on said stem and seated within the handle, a compressible bulb detachably connected with the threaded end of the stem and having a filling opening, a removable cap closing said filling opening, a hand-operated valve controlling communication between the bulb and the stem, inner and outer nozzles detachably mounted on the handle, the said inner nozzle being formed with a plurality of perforations, and a plurality of hollow teats formed on the outer nozzle and projected inwardly thereof to provide suction cups opening through the outer surface of the said outer nozzle.

3. In a syringe a handle having a longitudinal bore extending therethrough, a tubular stem inserted within said bore, a compressible bulb connected with one end of said stem, a resilient nozzle connected with one end of the handle and having a plurality of inwardly extending teats opening outwardly through the nozzle, said teats flattening when a pressure is set up within the nozzle and relaxing when the pressure is released, thereby acting as suction pockets.

In testimony whereof I affix my signature in presence of two witnesses.

GEORGE C. HOHEIN.
